UNITED STATES PATENT OFFICE.

FRANK G. SHEPHERD, OF SALT LAKE CITY, UTAH.

ELEVATOR LOCK.

Application filed January 29, 1921. Serial No. 440,864.

To all whom it may concern:

Be it known that I, FRANK G. SHEPHERD, a citizen of the United States, residing at Salt Lake City, in the county of Salt Lake and State of Utah, have invented new and useful Improvements in Elevator Locks, of which the following is a specification.

The object of the invention herein described is to provide a safety elevator lock which breaks the controller circuit and thus prevents the operation of the car while any door to the shaft is not shut and locked. The invention has advantages over types now in use in that it is located on the door at the place where the ordinary lock is placed instead of at the top, thus preventing the door becoming unbalanced and possibly lifted from the rollers by the operation of opening; the lock is unlocked, the circuit broken, and the door opened by one pull on the handle, thus saving time in opening and closing over the type which is placed at the top of the door and requires two movements to unlock and open the door; the wiring connections to the circuit breaking switch of the lock are much simpler and less expensive than to a lock placed at the top of the door; and the lock itself is much simpler and less likely to get out of order than others now on the market. Other advantages will appear hereafter.

In the accompanying drawings Fig. 1 is a plan of the lock mechanism and unlocking lever mounted on a door and frame.

Fig. 2 is a rear elevation of the weight element.

Fig. 3 is a section A—A of Fig. 2.

Fig. 4 is a top view of the switch contacts and mounting.

Fig. 5 is a diagram showing the method of installing and piping for the electric wiring.

Fig. 6 is an illustration of the wiring connection of the switch.

Fig. 7 is an adaptation of the mechanism to the push button elevator.

Fig. 8 is a somewhat enlarged detail of weight 27.

Fig. 9 is a left elevation of dog 28 and lever 29.

Fig. 10 is a perspective of the mechanism for releasing the lock when a push button elevator is at the floor at which it is desired to enter.

Fig. 11 illustrates an alternative method of weighting the lock release mechanism to insure its return to normal position.

The device consists of box 1, mounted on the door frame and which contains weight 2 and the spring switch contacts 3 and 4. Plate 5 is mounted on the door and carries 60 stud 6 and guide 7. The bell-crank lever 8 is pivoted on stud 6 and to one arm thereof is pivoted bar 9 which runs through guide 7. Bar 9 has on its sides projections 10, 11, 12, and 13 which serve to restrict its travel 65 and on its outer end has handle 14 used for operating both door and lock. The end of lever 8 adjacent box 1 is curved on top so that it will act against and raise weight 2 when the door is closed. This end also carries on its lower side an insulating block 15 to which is secured the metal plate 16. On the other arm of said bell-crank lever 8 is cut the notch 17 which engages the frame or side edge of said box 1, thus locking the 75 door. There is, however, sufficient clearance between the lower side of lever 8 at notch 17 and the box frame to permit plate 16 to come firmly in contact with contacts 3 and 4 and close the switch. The weight of 80 lever 8 and weight element 2 are carried entirely by plate 16 and contacts 3 and 4, thus always insuring a good contact. Weight element 2 is free to move vertically, being guided loosely by bolt 18 and the sides of 85 the box. Its travel downward is restricted by head 19 of bolt 18. Fig. 2, which fits in recess 20 of the weight element. This recess opens at the rear of the weight element and is cast therein. The position to which 90 weight element 2 may fall is adjusted by varying the position of nut 21.

To open the door, the operator pulls the handle 14, and thereby moves the bar 9 longitudinally, which movement shifts said bell-crank lever 8 on its pivot and raises the other arm of said lever and the weight 2, this disengages notch 17 from the box frame, opens the switch by breaking the contact of plate 16 with contacts 3 and 4. The 100 effect of thus opening the switch is shown in Fig. 6 which illustrates one of the many connections encountered in elevators. Wire 22 is the feed wire to the controller 23. When, for any reason, wire 22 is disconnected from the controller or the current broken the elevator will not operate as the actuating current is cut off. A break in this wire is therefore made between safety switch 24 and controller 23 and the wire is carried by a 110 suspended cable to the various switches, as 25. There are as many of these switches as

there are floors, Fig. 5, and all are wired in series. Therefore if any door be opened or unlocked the circuit through the controller will be broken and the elevator will fail to 5 operate until the door is closed and locked. Fig. 5 also shows the method of running conduit 26 which carries wire 22 between the switches. This conduit is run vertically from one switch to the next and the cable 10 connection to the car is made from the junction box midway up the elevator shaft. In the case of locks which are fastened to the top of the door and frame it is necessary to install two condulets or bends at each floor, 15 thus practically doubling the cost of wiring, and in addition this conduit running across the front of the shaft at each floor, together with the lock box, adds an element of danger because of the possibility of its becoming 20 loosened and caught by the moving car or hitting a passenger who stands too near the front. This element of danger and the extra wiring expense are eliminated by the device herein described.

25 Fig. 7 shows an adaptation of the device to a push button elevator. The object of this adaptation is to prevent the opening of any door to the shaft except the one at which the car rests. This is accomplished by the 30 use of weight 27, dog 28, lever 29, shaft 30, roller 31, and bell crank 32. A detail of weight 27 and lever 29 as placed therein is shown in Fig. 8. Fig. 9 shows the relation of dog 28 and lever 29 as they are fastened 35 to shaft 30. The operation of the device is best illustrated by Fig. 10. As the car comes to any floor a projection 33 fastened to the car comes in contact with roller 31 and forces it upward and back, thus rotating bell crank 40 32 and shaft 30. This in turn rotates dog 28 causing it to become disengaged from notch 34 in lever 8, and at the same time causes lever 29 to raise weight 27. Shaft 30 moves in slot 35 as weight 27 is raised. As 45 soon as dog 28 is disengaged from notch 34 lever 8 may be operated from either the outside or inside of the shaft, but when the car is not in position so that projection 33 engages roller 31 weight 27 acting on lever 29 50 causes dog 28 to return to engagement with notch 34, thus preventing the operation of lever 8.

What I claim as my invention is:

1. An elevator lock comprising a bell-crank lever pivoted on the door of an elevator; a handle connected with one arm of said bell-crank lever to move said lever on its pivot, another arm of said lever having a notch in its underside and a weighted por-

tion opposite said notch; a current carrying member fastened on and insulated from said last mentioned arm of said lever; and contact members spaced apart and mounted adjacent said lever and on which said contact member rests when said lever is in normal 60 position.

2. An elevator lock comprising a box; a bell-crank lever pivoted therein with one arm protruding from said box and having a notch cut in one edge thereof; a handle connected with the other arm of said bell-crank lever by which the lever is moved on its pivot; spaced apart contact members mounted in said box which is secured to the elevator door frame; a contact member mounted on and insulated from the notched arm of said lever and adapted to bridge the space between the said contact members in said box; and a weight in said box adapted to resist the movement of said lever in one direction and to aid said movement in the opposite direction.

3. An elevator lock comprising a box having an opening in one edge thereof; current carrying contacts in said box forming a portion of an electric switch; a weight mounted for limited vertical movement in said box; a manually operated bell-crank lever pivoted on a movable door and having one arm notched to engage said box within said opening therein; and a metal member on the same arm of said lever to complete the electric circuit when it is brought in touch with both of said current carrying contacts.

4. An elevator lock comprising a box secured on the frame of a door and having a portion of one side cut out; spaced apart switch contacts secured within said box; a plate fastened on the door of an elevator adjacent the said box on the frame of the door; a bell-crank lever pivoted on said plate; an arm of said lever notched to engage a portion of said box within the opening therein; an insulating block secured on the arm of said lever; a metal switch plate fastened on said insulating block and adapted to bridge the space between said switch contacts; and means to move said lever on its pivot to make and break an electric circuit by moving one member of the switch which is carried on the door into contact with the other members of the switch which are carried on the stationary frame of the door.
